United States Patent Office.

JOHN L. WHITING, OF BOSTON, MASSACHUSETTS.

REISSUED

Design No. 4,718, dated March 14, 1871.

DESIGN FOR A PAINT-BRUSH.

The Schedule referred to in these Letters Patent and making part of the same.

To all persons to whom these presents may come:

Be it known that I, JOHN L. WHITING, of Boston, in the county of Suffolk and State of Massachusetts, have invented or produced a new and useful Design for a Paint-Brush; and do hereby declare the same to be fully described in the following specification and represented in the accompanying drawing, of which—

Figure 1 is a front view;

Figure 2, a side elevation; and

Figure 3, a top view of a brush made in accordance with such design.

One characteristic of such design is an oval or elliptical ferrule, A;

Another is an oval or elliptical head, B, made to fit into the upper end of such ferrule;

Another is a conical handle, C; and, finally,

The last characteristic is a mass, D, of bristles,

oval or elliptical in transverse section, and tapered relatively to the ferrule in manner as represented in the drawing.

The brush having such form, besides being ornamental, is useful.

I am aware that brushes have been made with heads, ferrules, and handles having parallel opposite sides, and consequently make no claim to any design of such character.

What I claim is—

The design, substantially as described, for a paint-brush, such design being composed of the four characteristics hereinbefore first enumerated.

JOHN L. WHITING.
